(57) **CLAIM**

The ornamental design for a scannable answer sheet, as shown and described.

DESCRIPTION

FIG. 1 is a front view of a scannable answer sheet according to a first embodiment.

FIG. 2 is an enlarged area taken from the circumscribed area shown by broken lines in FIG. 1.

FIG. 3 is a front view of a scannable answer sheet according to a second embodiment.

FIG. 4 is an enlarged area taken from the circumscribed area shown by broken lines in FIG. 3.

FIG. 5 is a front view of a scannable answer sheet according to a third embodiment.

FIG. 6 is an enlarged area taken from the circumscribed area shown by broken lines in FIG. 5.

FIG. 7 is a front view of a scannable answer sheet according to a fourth embodiment.

FIG. 8 is an enlarged area taken from the circumscribed area shown by broken lines in FIG. 7.

FIG. 9 is a front view of a scannable answer sheet according to a fifth embodiment.

FIG. 10 is an enlarged area taken from the circumscribed area shown by broken lines in FIG. 9.

FIG. 11 is a front view of a scannable answer sheet according to a sixth embodiment; and,

FIG. 12 is an enlarged area taken from the circumscribed area shown by broken lines in FIG. 11.

In the drawings, the ornamental design that is claimed is shown in solid lines. Broken lines of equal length (e.g., dash-dash lines) represent unclaimed portions of the scannable answer sheet and form no part of the claimed design. Broken lines of unequal length (e.g., dash-dot lines) encircle enlarged areas shown in other views. Broken lines with jagged elements are break lines that indicate that any portion of the article between the break lines forms no part of the claimed design.
